2 Claims. (Cl. 329—123)

(Granted under Title 35, U.S. Code (1952), sec. 266)

The present invention relates to detection of frequency modulation and more particularly to a simplified, combined limiter and discriminator circuit.

Heretofore frequency discriminators for reception of signals on frequency modulated radio waves have made use of selective circuits tuned slightly off resonance with the mean frequency of the carrier waves, and of pairs of selective circuits so tuned that one is above and the other below resonance with the mean frequency.

It is well known that these discriminators have the disadvantage of responding to amplitude modulation if such is present along with the frequency modulation unless preceded by a limiter, and that their response characteristics are not linear so that they introduce distortion. Attempts to make these characteristics linear lead to bandwidth difficulties. Limiting circuits in turn have a tendency to introduce additional distortions of various kinds.

An object of the present invention is to incorporate in a single-tube circuit the combined function of limiter discriminator and amplifier.

Another object is to provide a single-tube circuit with these functions which will have a more linear overall discriminating characteristic and consequently introduce less distortion.

A further object is to provide a circuit of the above type which will have a greater range of discrimination action than hitherto attained.

A further object is to provide a circuit of the above type which will be sensitive to a very small frequency modulated voltage.

The invention makes use of the tendency of an oscillator to pull into synchronism with a variable frequency signal of given frequency range when such signal is injected at a suitable point in the circuit. The oscillator will under this condition have a nearly linear characteristic of output voltage versus frequency of the injected signal. It has been discovered that this characteristic of the oscillator can be made substantially linear by the insertion of a phase-shifting or attenuating network of predetermined constants in the oscillator circuit and that this principle may be applied to any conventional oscillator. Hereinafter when reference is made to the oscillator characteristic it will be this oscillator output characteristic of voltage versus frequency that is meant.

The phase shifting network may be placed in the grid or plate or feedback circuit of the oscillator depending upon the particular type of oscillator and the function it is required to perform. The oscillator output voltage varies at a rate corresponding to the frequency modulation of the injected carrier signal so that an audio frequency or intelligence signal is obtained directly without the aid of a conventional detector of any kind. Any spurious amplitude modulation that may be present in the original signal, however, does not appear as interference, distortion or noise in the output. The synchronized oscillator, therefore, performs simultaneously as

2

an amplitude limiter and a frequency modulation detector or discriminator.

Various other objects and advantages of the invention will become apparent from a perusal of the following specification and the drawings accompanying the same.

In the drawings:

Fig. 1 is a circuit diagram of one embodiment of the invention in which a T-bridge network is used in the input or grid circuit of the oscillator;

Fig. 2 is a graph of one type of characteristic of a circuit embodying the principle of the present invention;

Fig. 3 is a circuit diagram of a second embodiment of the invention;

Fig. 4 is a graph of the characteristic of the oscillator circuit of Fig. 3;

Fig. 5 is a graph of the characteristics of the oscillator circuit of Fig. 3 for different plate voltages;

Fig. 6 is a circuit diagram of a third embodiment of the invention;

Fig. 7 is a vector diagram showing certain operating conditions of the circuit of Fig. 6 at oscillator frequency;

Fig. 8 is a vector diagram showing the operating condition at a frequency lower than the natural frequency of the oscillator, and

Fig. 9 is a graph showing potential at point X versus changes in input.

Referring to the drawings in detail, and first to Fig. 1, this shows a preferred embodiment of the invention in which a T-bridge phase-shifting network consisting of resistors 11, 12 and 13, and capacitors 14, 15 and 16, is placed in the grid circuit of a triode oscillator 17. The right hand end of the T of the network is connected to the grid at the junction of capacitor 15 and resistor 12

while the left hand end of the T, at the junction of the capacitor 14 and resistor 11, is connected to the upper end of a tuned circuit consisting of the inductance 18 and capacitance 19 in parallel connection. The bottom end of the T, at the junction of resistor 13 and capacitor 16, forms one input terminal 25, the other input terminal 26 being connected to the grounded cathode. The frequency modulated synchronizing voltage e_1 is applied to these terminals.

Feedback is furnished by the electromagnetic coupling between the inductance 20 in the plate circuit of the triode and the inductance of the parallel-tuned circuit. One end of the inductance 20 is connected directly to the plate of the triode and the other end through a load resistance 22 to the positive side, B+, of a suitable plate voltage source not shown and which may be of any known or other suitable form grounded at its negative terminal. A bypass capacitor 21 provides a high frequency shunt around the load resistance 22 and plate voltage source. Output voltage is taken across resistor 22 and ground, through capacitor 23. This combination of resistor 22 and capacitor 23 forms an audio output circuit.

Capacitor 19 is made variable to enable the tank circuit to be tuned to a frequency near the upper limit of carrier wave swing. In order to trim the T-bridge for a good null, provision may be made for varying the value of one of the capacitors 14, 15 or 16. To this end a small

capacitor 24 may be connected in multiple with one of those already present.

Fig. 2 shows the type of characteristic achieved in the embodiment of Fig. 1, with a peak value of injected voltage of about 0.1. It will be apparent from this characteristic that a very small amount of frequency modulation about a given mean or center carrier frequency can be detected with this circuit. In general, the output e_0

70

increases up to the point at which the tank circuit resonance frequency becomes that corresponding to a peak at the top of the linear range of the characteristic. In other words when the tank circuit resonant frequency is such that the output voltage of the oscillator will be at its maximum in the linear range when the carrier frequency is at its maximum. By using a high $L-C$ ratio in the tank a still higher sensitivity may be achieved, for a given type of tube.

In a practical embodiment of the circuit of Fig. 1, the constants were as follows:

Resistance 11	33K
Resistance 12	33K
Resistance 13	15K
Condenser 14	50 mmf.
Condenser 15	50 mmf.
Condenser 16	100 mmf.
Tube 17	6J5
Coil 18	10 mh.
Condenser 19	500 mmf.
Coil 20	16 mh.
Condenser 21	0.1 mf.
Resistance 22	470K
Condenser 23	To pass desired audio band.
Condenser 24	30 mmf.
Source B+	175 v.
T-bridge null at	75 kc.
Tank circuit	103 kc.
FM signal approx.	102-103 kc.

In the embodiment diagrammed in Fig. 3, an electron tube, having an anode or plate, cathode and grid, has in its plate circuit a parallel tuned circuit consisting of an inductance 31 and condenser 32, connected in series with a load resistance 39 and the positive terminal of a source of plate voltage +35-45 v., it being understood that such source has its negative terminal connected to a common ground with the cathode. A bypass condenser 33 connects the cathode to the junction between the tuned circuit and the load resistance 39. The grid coil 38 has its upper terminal connected through a grid condenser 37 to the grid while a grid resistance 36 connects the grid to the cathode. A variable feed-back condenser 35 connects the plate to the upper terminal of the grid coil. This feedback condenser and the grid coil constitute a phase-shift network. Interposed between the lower terminal of the grid coil and the cathode are a pair of input terminals 40-41 between which the signal voltage is introduced. Output voltage is taken from the junction of the resistance 39 and the parallel tuned circuit, to ground. The characteristic of this circuit is shown in Fig. 4.

In a practical embodiment of the circuit of Fig. 3, the constants were as follows:

Inductance 31	16 mh.
Condenser 32	500 mmf.
Condenser 33	0.1 mf.
Condenser 35	500 mmf.
Resistance 36	33K
Condenser 37	0.00125 mf.
Inductance 38	10 mh.
Resistance 39	100K
e_{bb}	45 v.
e_1	0.1 v.

For this embodiment, with the above values of circuit constants, the output voltage is proportional to the plate current. The natural frequency of the oscillator is as indicated near the upper end of the operating band-width. This is a general condition for better operation of these circuits.

In either of the embodiments here shown, the impedance and type of coupling of the source of synchronizing voltage may affect the oscillator characteristic. For example, if electromagnetic coupling between an inter-

mediate frequency tank circuit and an input tank circuit of the oscillator is utilized, the oscillator frequency may be changed and its characteristic changed accordingly. To avoid this the impedance and coupling must be chosen carefully so that the variation in characteristic is acceptable. Also a proper feedback method, such as insertion of a neutralizing capacitance may be used.

Fig. 5 shows characteristics at different plate voltages of the embodiment of Fig. 3, having substantially the same circuit constants but using a sub-miniature tube of the type known as hearing-aid tube, with the oscillator tuned to an idle frequency near 104 kc. for reception of a carrier frequency modulated between 102 and 103 kc. This arrangement has been found useful in a portable underwater receiver to be carried by a swimmer for reception of underwater compressional waves.

It was found that in general, the lower the plate voltage the wider the tracking of the oscillator. The output voltage increases with the resistance of the grid leak up to the point of instability.

To take care of signal injection on a separate grid the modification diagrammed in Fig. 6 is provided. It is to be noted that this embodiment uses the same phase shift network as Fig. 3 which was found to be the better of the two phase shifting systems and makes use of a pentagrid-converter-type tube. Almost any of the conventional converter tubes could be used. It will also be noted that the signal injection circuit is completely isolated so that the coupling influence previously mentioned is greatly reduced. The signal resonant circuit $L-C$ can be a standard I.F. transformer if the discriminator is used in a superheterodyne; or it can be an R.F. transformer if the discriminator is operated at the input carrier signal frequency in a tuned-radio-frequency receiver—in which case the coil L may be connected to a preceding R.F. amplifier or even directly to the antenna.

A theory of operation of the circuit of Fig. 6 is as follows:

The frequency modulated input signal e_1 is applied to the first grid of a 6L7 type tube from the tuned output circuit of the coupling $L-L_2$. The cathode resistor R_2 , suitably bypassed for both audio and radio frequencies by condenser C_3 , maintains the cathode sufficiently positive to prevent the first grid's drawing current for reasonable input levels. The impedance of this input grid, therefore, is high and will not load at any tuning or resonant circuit which may be used in the injection signal circuit.

Grids 2 and 4 of the tube comprise a screen or shield grid. Suitable D.C. potential is applied to these through dropping resistor R_4 which is connected to the B-supply. Bypass condenser C_5 is sufficiently large to be of a low reactance to audio as well as radio frequencies.

In the tube plate circuit is a resonant tank composed of inductance L_2 and variable capacity C_4 , and an audio frequency load resistor R_3 . Bypass condenser C_6 shunts R.F. currents to ground but this capacity should not be great enough to allow appreciable audio frequency current flow. Audio frequency output voltage e_0 which is developed across load resistor R_3 is fed to an external load at terminals 3-4 through coupling condenser C_7 .

Shunted from tube plate to ground is a phase-shifting network composed of inductance L_1 and capacitor C_1 . From the common point between L_1 and C_1 a coupling condenser C_2 is attached to the third grid of the tube. Capacitor C_2 need be only large enough to have negligible reactance at the radio frequency being received. A grid leak resistor R_1 is connected from the third grid of the tube to ground so that rectified grid current which flows to ground will develop sufficient grid bias for proper operation when the circuit is oscillating. The higher this grid leak R_1 , the greater the audio output voltage from the discriminator. Too great a grid leak value must not be used, however, else the circuit break into intermittent

oscillation. Typical grid leak values may be from $\frac{1}{2}$ to 10 megohms.

Now let us suppose the input signal e_1 has a mean frequency of 10 mc. and it is being frequency modulated with a maximum deviation of 75 kc. In this case the plate tank circuit L_2-C_4 should be tuned to approximately 10.080 mc.—just slightly higher than 10 mc. plus 75 kc. or 10.075 mc.

The phase shift circuit L_1-C_1 (which is really a series resonant circuit) then should be tuned slightly higher in frequency than the plate tank L_2-C_4 . A suitable frequency for the grid phase shift circuit might be 10.085 mc. In any case, for proper operation, it is always essential that the grid phase network be tuned even higher in frequency than the plate circuit. In this way the grid circuit will be capacitive in nature and give the proper phase shift for desirable operation.

If we assume for a moment that the injected signal e_1 is zero, the oscillator will oscillate at its own natural frequency of 10.080 mc. That it will oscillate under proper conditions can be illustrated by referring to Fig. 7. Here we have the vector e_p representing the plate voltage. Since the tank circuit L_2-C_4 is resonant, it will behave as a high-impedance resistive load. The plate circuit i_p , therefore, is small in value and in-phase with the plate voltage e_p . This is shown by the heavy vector in Fig. 7.

The grid phase network L_1-C_1 , however, is resonant at a slightly higher frequency. This circuit, hence, is slightly capacitive, and the current i_g flowing through it will lead the plate voltage e_p by a small angle θ . For this condition, the voltage e_c developed across capacitor C_1 will lag behind i_g by nearly 90° and the voltage e_L developed across inductance L_1 will lead i_g by nearly 90° . These vectors are indicated in the figure. The voltage e_L , of course, is applied to the tube grid as feedback voltage. Note that although e_L is not exactly 180° out-of-phase with the plate voltage e_p , it does have a component e_g which is so. With proper adjustment of the circuit in Fig. 6, this feedback voltage e_g can be made sufficiently great to sustain continuous oscillation.

Now suppose an input signal e_1 be applied to the circuit. If this injected signal has the same frequency as that of the oscillator, then the conditions of Fig. 7 will prevail and the plate current i_p will be as shown. If, however, the injected signal has a lower frequency than that of the oscillator, the oscillator will attempt to fall in step by lowering its own frequency. The oscillator will be able to synchronize itself and maintain continuous oscillation at this new low frequency only if the feedback voltage remains of sufficient amplitude and proper phase. The grid phase shift network of L_1-C_1 in Fig. 6 makes these conditions possible.

At the new low frequency, the plate tank circuit L_2-C_4 will not be resonant; instead, it will be inductive and the absolute impedance will be considerably lower. We have then the condition shown in Fig. 8. The plate current i_p , considerably greater in magnitude, lags behind the plate voltage e_p by the angle ϕ . Since for this low frequency, the phase shift network L_1-C_1 will be even farther from resonance, it will appear highly capacitive. Feedback current i_g , hence, will be smaller and lag behind the plate voltage e_p by the larger angle ϕ' . For this condition, the condenser voltage e_c which lags i_g by 90° is quite large and inductance voltage e_L , leading i_g by 90° is much smaller. The inductance voltage e_L , of course, is the grid feedback voltage. Note that although e_L is smaller, its component e_g which is exactly 180° out-of-phase with the plate voltage e_p is very nearly the same as before. We find then that sufficient feedback is realized at this new low frequency to maintain continuous oscillation.

Although the plate tank circuit L_2-C_4 introduces phase shift when operated off-frequency, the grid network L_1-C_1 supplies enough phase shift in the opposite direction to keep the feedback voltage e_g very nearly constant over a wide frequency range. The oscillator, therefore,

will track frequency excursions of the injected signal with ease.

The oscillator will not follow the injected signal for frequencies higher than its own natural frequency because phase shifts in the grid phasing network result in negative rather than positive feedback and the oscillator either ceases functioning or breaks out of synchronization. For frequencies lower than its own natural frequency, however, the oscillator will follow as long as the feedback voltage e_g has sufficient magnitude to maintain oscillation. It is only when the impedance of the plate tank circuit L_2-C_4 falls to such a low value that very little R.F. plate voltage can be developed across it and insufficient feedback current i_g can be realized that the oscillator ceases tracking.

But note that when the oscillator is operated at or near its own natural frequency, the current i_p is small as shown in Fig. 7. This means there will be little voltage drop across the load resistor R_3 in Fig. 6 and point X will have a relatively high potential. On the other hand, when the injected signal forces the oscillator to operate at a frequency lower than its natural one, the plate current i_p is relatively high as pictured in Fig. 8. The voltage drop across load resistor R_3 , therefore, will be high, and the potential of point X will fall.

It is obvious then that the potential of point X will vary as the frequency of the input signal e_1 is varied. If injection voltage e_1 is a frequency modulated R.F. signal, then the voltage at point X will be an audio frequency voltage e_o corresponding to the degree and manner of modulation. This audio voltage e_o , of course, is fed through coupling capacitor C_7 to any output load such as headphones, speaker, or following audio amplifiers.

Is is apparent that the principal effect of the input signal e_1 is to bring the oscillator frequency into synchronization. In so doing, of course, the plate current drawn by the oscillator is changed and an audio output voltage is delivered. Within comparatively wide limits, the frequency of the input signal e_1 is its most important parameter. As long as it is sufficient to synchronize the oscillator, the magnitude of the input signal is relatively unimportant. This means that the oscillator-discriminator is relatively insensitive to amplitude changes in the input signal and performs very well as a limiter. It also means that a large magnitude frequency modulated signal and a small magnitude signal which is still sufficiently great to bring the oscillator into synchronization will result in the same audio frequency output voltage; the oscillator-limiter-discriminator, therefore, has an inherent automatic volume control characteristic.

The manner in which the potential of point X follows changes in input signal frequency is about like the curves shown in Fig. 9.

An important feature of the frequency discriminator herein disclosed is its sensitivity to frequency modulated signals of small magnitude. A second feature is the ability of the synchronized oscillator to track the injected carrier signal over a very wide frequency swing. A third feature is that the oscillator is relatively insensitive to amplitude changes in the input signal. A fourth feature is that the oscillator gives approximately the same audio frequency output voltage for both large and small input signal amplitude, thus exhibiting an inherent automatic volume control characteristic.

While certain specific embodiments of the invention have been described herein for the sake of disclosure, it is to be understood that the invention is not limited to such specific embodiments but contemplates all modifications and variations thereof as fall fairly within the scope of the appended claims.

The invention described herein may be manufactured and used by or for the Government of the United States of America for governmental purposes without the payment of any royalties thereon or therefor.

What is claimed is:

1. A frequency modulation receiver system comprising a multigrid tube having two input grids, a cathode and an anode, a source of plate voltage having its negative terminal connected to a common ground, a cathode resistor connecting the cathode with the common ground, a bypass condenser connected in shunt of the resistor, a parallel-tuned circuit connected in the anode circuit of the tube in series with a load resistance and said source of plate voltage with the tuned circuit nearest the anode and the load resistance between the tuned circuit and the positive terminal of the said source, a bypass condenser connecting the junction between the tuned circuit and the load resistance to the common ground, a grid coil having one terminal connected through a grid condenser to one of said input grids and the other terminal connected to the common ground, a grid resistance connecting said one grid to the common ground, a variable feedback condenser connecting the anode with said one terminal of the grid coil, said feedback condenser and grid coil constituting a phase-shift network, a pair of signal input terminals, one connected to the other said input grid and the other to the common ground, and a pair of output terminals one connected through a blocking condenser to the junction of the load resistance with the tuned circuit and the other connected to ground.

2. A frequency modulation receiver system comprising a multigrid tube having two input grids, a cathode and an anode, a source of plate voltage having its negative terminal connected to a common ground, a cathode resistor connecting the cathode with the common ground, a bypass condenser connected in shunt of the resistor, a parallel-tuned circuit connected in the anode circuit of the tube in

5
